UNITED STATES PATENT OFFICE.

HARRY TAYLOR LOOMIS, OF BROOKLYN, NEW YORK.

FABRIC-MAKING MACHINE.

Application filed August 4, 1919. Serial No. 315,163.

To all whom it may concern:

Be it known that I, HARRY TAYLOR LOOMIS, a citizen of the United States, residing at Brooklyn, in the county of Kings and State of New York, have invented certain new and useful Improvements in Fabric-Making Machines, of which the following is a full, clear, and exact description, such as will enable others skilled in the art to which it appertains to make and use the same.

This invention relates to apparatus and machines for making composite fabrics, and with respect to its more specific features to machines of the character referred to adapted to make an ornamental product from wide strips of material.

One of the objects of the invention is the provision of a practical machine for feeding strips of backing material, as flannel, and facing material, as silk, stirring the facing material and automatically attaching the two strips together along a predetermined line or lines.

Another object is the provision of a simple machine for automatically supplying a reinforcing strip and associating it with the attached backing strip and facing strip along the predetermined line above mentioned.

Another object of the invention is the provision of an efficient machine for automatically supplying a finishing strip and attaching the same in folded condition to the attached backing strip and facing strip.

Another object of the invention is the provision of a practical machine capable of producing a plurality of similar products from single widths of the backing material and the facing material.

Other objects will be in part obvious and in part pointed out hereinafter.

The invention accordingly consists in the features of construction, combinations of elements and arrangement of parts which will be exemplified in the construction hereinafter described and the scope of the application of which will be indicated in the following claims.

In the accompanying drawings, wherein similar reference characters refer to similar parts throughout the several views,—

Figure 1 is a longitudinal sectional elevation illustrating one embodiment of the invention;

Fig. 2 is a plan view of a portion of the machine on a scale enlarged over that of Fig. 1;

Fig. 3 is a front view of a portion of the machine, certain parts being broken away for the sake of clearer disclosure;

Fig. 4 is an enlarged longitudinal sectional view of certain feeding and attaching elements of the machine;

Fig. 5 is a side view of one of the driving devices and illustrates a portion of the operating device of the shirrer;

Fig. 6 is an end view of Fig. 5;

Fig. 7 is a detail sectional view of a cutter, or slitter, employed in the present embodiment;

Fig. 8 is a front view of a shirrer blade;

Fig. 9 is a plan view of a liquid coating device;

Figs. 10 and 11 are different views of the tensioning device for the backing strip;

Fig. 12 is a plan view of the rear portion of the machine showing the mounting of the finishing strips and a portion of the stitching mechanism, together with finishing strip folders;

Fig. 13 is a diagrammatic cross sectional view of the completed product, showing also the fold in the finishing strip effected by the folding device of Fig. 12;

Fig. 14 is a side elevation of the folding device;

Fig. 15 is an elevation of a stitching portion of the sewing machine employed;

Fig. 16 is a longitudinal sectional view of one of the feed rolls; and

Fig. 17 is a vertical cross section through the feed rolls.

Referring now more specifically to the drawings, attention is directed to Fig. 13 wherein is diagrammatically illustrated the finished product. In this view the numeral 1 indicates a backing strip which may be of flannel. The numeral 2 indicates the facing strip which may be of silk or other ornamental fabric. The numeral 3 indicates the reinforcing strip—gauze, tape—lying between the backing strip and the facing strip at one edge of the completed product. The numeral 4 indicates the finishing strip, which may be made of silk folded as indicated and attached to the other strips by a line of stitching, indicated at 5. In Fig. 13 the several strips are separated for the purpose of clearer disclosure. It is to be understood that the reinforcing strip 3 is utilized to effect the attachment of the strips 1 and 2 to each other, and serves also to stiffen and reinforce the edge of the product. It

will also be seen that the fold of the finishing strip 4 is looped and preferably not creased at 6. Thereby it has the appearance of softness. The machine of the present invention is designed to produce the product generally illustrated in Fig. 13, and parts of such products, from continuous supplies of material and in an automatic manner, it being merely required to thread the machine with the materials and set it in motion.

Referring now to the general construction of the machine, reference is made more particularly to Figs. 1, 2, 3 and 4 wherein the numeral 7 indicates a table supported by legs 8, the whole forming the frame of the machine, the fore part 9 of the frame being disposed below the rear part 7. The numeral 10 indicates a platform to which the completed fabric may be delivered. The numeral 11 (Fig. 2) indicates an electric motor from which the machine derives its motion through the instrumentality of the chain 12 driving a worm shaft 13 journaled in a suitable upstanding bearing block 13'. The numeral 14 indicates a worm wheel journaled in the bearing block and deriving its motion from the worm 13. Fixed so as to rotate with the worm wheel 14 is a beveled gear 15 cooperating with a companion beveled gear 16 on a counter shaft 17 supported in bearings 18 on the frame and carrying a sleeve or shaft 19 splined to the counter shaft 17 so as to be longitudinally adjustable thereon, but forced to rotate therewith, the sleeve 19 carrying a friction gear 20 cooperative with a companion friction gear 21 mounted on a transverse shaft 22 supported in standard bearings 22' on the frame, the shaft 22 driving a chain 23 which transmits motion to a spur gear 24 on a stud on the inner portion of the block 13', this gear in turn meshing with a pinion 25 on an outer hollow shaft 25' rotatively supported on an inner hollow concentric shaft 26 extending transversely across the machine. By adjusting the radial position of the friction gear 20 relative to the companion friction gear 21, the speed of rotation of the shaft 22 may be varied as desired and the shaft 25' driven at greater or less speed as may be required. The shaft 26 is journaled in bearing pieces 27 at opposite sides of the frame (Fig. 4) vertically adjustable in slots 28 in the blocks 13', springs 29 being employed tending to lift the bearing pieces 27. A cam or wiper 30 on a handle 31, journaled in the bearing pieces 27 cooperates with an adjusting screw 32 to force the bearing plate 27 to a lower position, and consequently to regulate the up and down position of the shaft 26. Any suitable device may be employed for adjusting the position of the friction gear 20 radially of the friction gear 21 and proper

devices are provided to lock the parts in adjusted relation. Beneath the table 7 is a housing 33 within which may be disposed a supply of facing material 34 in loosely folded condition so that it may be readily withdrawn therefrom with but little resistance.

The numeral 35 indicates a frame supported roll or spool which supports the supply rolls of backing material 36. The backing material passes through a tension device, indicated generally by the numeral 37, which keeps it more or less taut and smooth, and thence the backing strip 36 passes upwardly to the feeding and attaching devices, as illustrated in Fig. 4. Over the table 7 passes the upper ply of an endless canvas feed belt 38 supported by a front feed roll 39 and a rear feed roll 40 suitably journaled in the bearing blocks 13'. Arranged on the feed belt 38 in regular rows both longitudinally and transversely, and spaced apart thereon, are pointed pins 41 designed to penetrate the flannel backing strip 36 and positively feed the same to the left, referring to Figs. 1 and 4. The bevel gear 15 is on the end of the belt feed roll 39 and gives motion to this roll and to the pin belt just referred to. A suitable belt tightener 42 may be employed if desired. If desired friction surfaces, as sand paper, may be substituted for the pins 41, or utilized therewith.

As has been stated, the hollow shaft 26 is supported in vertically adjustable bearing pieces 27, it being understood that there are two bearing pieces 27, one at each side of the machine, in order to give proper support and uniform rise and fall to the shaft 26 throughout its length. The feed roll 39 may have pointed teeth 39' to engage the belt 38, and positively feed the same.

The silk facing strip 34 from the housing 33 passes from the front end of the machine table over the shaft 22 and over several narrow canvas strip supporting belts 44 and over loose rollers 45 on a stationary transversely disposed bar 46 spaced in front of the shaft 26 and roll 39, the facing strip 34 passing between the rolls 26 and 39, whence it extends rearwardly to the upper surface of the table 7. The rollers 45 act to support and guide the facing strip without unnecessary friction, being held in longitudinal position on the bar 46 by pins 43.

At a suitable part of the shaft 26, in the present instance at its midlength, the diameter is enlarged to provide a pressing roll or surface 47 designed to cooperate with the surface of the roll 39 to press the strips of fabric entering between these two rolls over a certain area. To give a longitudinal crease to the pressed strips, the pressing face of the enlargement may have a slightly elevated rib 48. At each side of the pressing

portion of the roll 26 are disposed certain devices, operative on one or more of said strips at the side of the areas pressed by the pressing surfaces hereinbefore referred to, 5 to advance such side portions so that the entire widths of the several strips are advanced substantially uniformly. In the present embodiment the side advancing devices include movable pins, or pin feeding 10 devices, as tractive or friction fingers or pins 49 carried by the rolls or outer shafts 25', and designed to contact the silk facings at the side of the pressed area. There are two sets of fingers 49, one set on the shaft 15 or sleeve 25' at one side of the pressing surface 47, and another similar set at the other side of said pressing portion. These fingers are preferably provided by metallic pins having rubber sleeves, the ends of the 20 sleeves projecting from the ends of the pins so as to come in contact with the facing strip 34. Within the hollow shaft 26 adjacent the pressing area referred to, a heater is disposed. In the present embodiment the 25 heater comprises a resistance coil 50 (Fig. 16) from which wires 52 extend to the end of the roll and to a suitable main provided with a cut-out switch wherewith the current may be established or cut off as may be required, suitable provision being made for 30 transmitting the current while the parts rotate.

In front of the pressing portion of the feed rolls 47 and 39 is disposed a means to 35 advance a portion of the facing strip 34 in transversely folded condition for attachment to the other strip or strips by the pressing portions of the rolls. In the present embodiment, a shirrer blade 52 is provided, being a thin metallic piece pivoted to a bifurcated arm 53 of a rock shaft 54 supported in the block 13' or other suitable part of the frame of the machine. The blade 52 is thrust downwardly by a coil spring 55 40 and its downward motion is limited by a lug 56 which cooperates with a portion of the arm 53. Rocking motion is communicated to the shaft 54 through the instrumentality of a link 57 pivoted to a crank 58 on the 45 worm shaft 13, the lower end of the link 57 being pivotally connected to an arm 59 extending from the end of the rock shaft 54. In order to provide for variation in the 50 throw of the folding or shirring blade 52, provision is made for adjusting the position of the pivotal connection between the arm 59 and the link 57, this being accomplished in the present embodiment by slotting the 55 arm 59 and providing a pivot pin 60 movable in said slot and in a channel 61 in a cross piece 62 carried by the link 57. By adjusting the pin 60 in this channel and in the slot in the arm 59, greater or less amplitude of vibration may be given to the 60 blade 52.

The numeral 64 indicates a spool or supply of reinforcing material which consists preferably of a narrow strip of cotton or linen gauze provided with adhesive material. In the present embodiment the adhesive material is dry as the gauze feeds from the spool 64. The reinforcing strip passes across a metallic guide bar 65 and under a metallic spring and contact piece 66, and thence through a tubular channel or standard 67 in a moistener or liquid-coating device 68 having a well containing water and provided with a wick 69, which presses against the reinforcing strip 64 and moistens the adhesive thereon. From the moistening device the reinforcing strip passes through a slotted guide bracket 70 and thence to position between the pressing surfaces 47 and 39, passing also between the reinforcing strip and the facing strip. In the present embodiment, the reinforcing strip is of such width that when slit longitudinally, each section thereof will provide a reinforce for the same side of the completed product, as exemplified in Fig. 13. By reason of the fact that the heater hereinbefore referred to is disposed adjacent the pressing surfaces of the rolls 26 and 39, those portions of the strip which may have been moistened by contacting with the reinforcing strip will be dried, and the pasted parts will be firmly attached together.

Inasmuch as so much of the apparatus hereinbefore described may be utilized in the production of a composite fabric suitable for general use without further finishing, the operation of so much of the machine may now be briefly referred to. A supply of the backing strip is mounted on the roll 35; a supply of facing material is placed in loosely folded condition in the housing 33, and a supply of gauze tape is mounted on the spool 64, the gauze tape being threaded through the channel 67 of the moistener and through the guide 70, thence into position between the backing strip and the facing strip, the former of which is led through the tension device 37 to between the rolls 47 and 39 so as to be engaged by the pins 41 of the feed belt 38 and the latter, or facing strip, being led over the front of the frame, over the shaft 22, belts 44 and rolls 45 beneath the shirring blade 52 into position between the pressing rolls 47 and 39. Both the backing strip and the facing strip are wide as compared with the tape, and will lie between the feed belts 38 with their sets of pins and the hollow shafts 25' with their sets of friction fingers. Upon energizing the machine, as by a clutch shifter, to transmit motion from the motor to the worm wheel 13, the three superposed strips will be fed and will be pressed together by the surfaces 47 and 39. The central portions of the backing strip and the facing strip will be

directly pressed together and firmly into contact with the pasted and moistened reinforcing strip by the pressing surfaces 47 and 39, so as to cause the paste to securely attach together certain areas of these strips along a predetermined line, the construction of the gauze permitting the paste to pass through the gauze and effect the attachment of both the backing and the facing strip thereto and to each other. The rib 48 in the pressing surface 47 serves to longitudinally crease the attached superposed strips along a line approximately central longitudinally of the gauze strip, and this crease facilitates the subsequent slitting or parting of the superposed strips along this line by a slitter, hereinafter referred to. The heat from the resistance coil will effect sufficient drying of the pasted joint to retain the strips securely attached together. It is to be noted, however, that, by the provision of the shirring blade 52 one of the strips, in the present instance the facing strip, is advanced in transverse folds, puckers or shirrs so that the pressing surfaces referred to bind the pressed portion of the facing strips to the other strips in a folded condition. Both the backing strip and the facing strip being wide as compared with the reinforcing tape, it is desirable to advance those portions of these strips transversely at the sides of the pressing area uniformly with the central portion. This is effected by the belt 38, assisted by the pins 41 which operate to positively advance the side portions of the backing strip, while the friction fingers 49 perform a similar office for the facing strip. The facing strip being of ornamental material, it is desirable to avoid defacing it, and to this end the fingers 49 are relatively soft, as being of rubber. The flannel backing strip being less expensive and usually concealed, may be penetrated by the pins 41 to more effectively assist the feed. Should the feeding of the lateral portions of the facing strip lag, increased rotary speed may be given to the fingers 49 by varying the radial position of the friction gear 20 relative to the gear 21. The pressure between the surfaces 47 and 39 may be regulated by adjusting the screws 32, and the amplitude of reciprocation of the shirring blade 52 may be changed to alter the depth of fold, or shirring, of the facing strip. Whereas in the present embodiment the backing and facing strips are attached along a central line so as to provide a double width of the product which will be separated along said central line to provide the product in duplicate, it will be understood that the machine may be utilized to provide a single width of the product.

In order to give greater finish to the product and to divide the double width strips into two single width strips, certain instrumentalities are provided, which will now

be explained. The numeral 71 indicates a slitter, or slitting disc, mounted in a carrier 72 overhanging the central line of the machine and adjustable by means of the screw 73. The slitter 71 cooperates with a platen roller 74 on the shaft 75 mounted in the frame of the machine, having a spur pinion 76 meshing with an idle pinion 77 driven from a spur gear 78 rotating with the roll 39. The slitter 71 is disposed to slit or part the three superposed strips along the central longitudinal line of the reinforcing strip. After being slit, the two sections of the fabric flow along the table under the influence of the feed belts 38 to positions 80 where the finishing strips are applied and attached, as by stitching, to the margins of each of the parted sections.

The numeral 80 indicate brackets supported by the frame and having bearings 81 for spools of finishing strip, as silk tape. The relation of these spools is clearly illustrated in Fig. 12, and it will be observed that from the spools, the tapes 82 pass around guide pins 83, through folders 84, into alignment with the edges of the parted sections of the product of the slitting operation, a stitching mechanism, as a sewing machine, generally illustrated at 85, being employed to stitch the folded finishing strips to the respective edges of the sections referred to. One of the folders is indicated in Fig. 14 and comprises a metallic piece 85, the fore end of which, at 86, receives the slit finishing strip in practically unfolded condition, the folder being shaped so that, as the finishing strip passes downwardly toward its rear under and toward the surface of the tape, the finishing strip will be folded and emerge from the folder in folded condition, as generally indicated in Fig. 13. The delivery end of the folder is arranged close to the stitching head of the sewing machine, and said sewing machine is provided with two needles or stitching mechanisms 86' and 87, one of which operates to sew the folded finishing strip to one edge of the parted product and the other to the other edge. It is preferred that the finishing strip be stitched to said edges along lines spaced from said edges, so that the outer edge of the attached finishing strip may be lifted. In this wise provision is made for passing tacks or other fastening devices through the reinforced edge of the composite article produced without passing through the finishing strip. On the contrary, the finishing strip will lie over and conceal such fastening devices.

Any suitable form of tension device for the backing may be employed. In the present embodiment the backing passes beneath a plate 90 extending transversely of the machine and is pressed against said plate by a jaw 91 held against the plate 90 by the

5 springs 92. The jaw 91 has a pivotal connection with the plate 90 by reason of lugs 93 of such shape as to enter slots 94 in brackets attached to the frame, said slots 94 having inner enlargements to receive the lugs 93, which latter, when the device is in operative condition, span the narrower slots 94 and are prevented from dropping therefrom. By turning the jaws 91 downwardly the lugs 93 will register with the slots 94, permitting removal of the jaw 91.

10 A device may be provided for indicating when the supply of reinforcing tape has become exhausted. To this end, the metallic guide bar 65 and pressing spring 66 may make contact when the end of the tape is fed beyond the guide bar 65 and thereby establish a current leading to an electric bell, or other indicator for the purpose.

15 20 Thus by the above described construction are accomplished, among others, the objects hereinabove referred to.

25 As many changes could be made in the above construction and many apparently widely different embodiments of this invention could be made without departing from the scope thereof, it is intended that all matter contained in the above description or shown in the accompanying drawings shall 30 be interpreted as illustrative and not in a limiting sense.

35 It is also to be understood that the language used in the following claims is intended to cover all of the generic and specific features of the invention herein described and all statements of the scope of the invention, which, as a matter of language, might be said to fall therebetween.

40 Having described my invention, what I claim as new and desire to secure by Letters Patent is:

45 1. In an apparatus of the character described, in combination, mechanism adapted to feed a backing strip, a facing strip and a reinforcing strip into superposed relation, said mechanism including a belt having pins to engage and feed the backing strip and a roll having friction pins to engage and feed the facing strip, and means adapted to attach said strips together along a predetermined line.

50 55 2. In an apparatus of the character described, in combination, mechanism adapted to feed a backing strip, a facing strip and a reinforcing strip into superposed relation, said mechanism including a belt having pins to engage and feed the backing strip and a roll having friction pins to engage and feed the facing strip, and means adapted to attach said strips together along a predetermined line including cooperative presser surfaces between which said strips pass.

60 65 3. In an apparatus of the character described, in combination, mechanism adapted to feed a backing strip, a facing strip and

a reinforcing strip into superposed relation, said mechanism including a belt having pins to engage and feed the backing strip and a roll having friction pins to engage and feed the facing strip, means adapted to attach 70 said strips together along a predetermined line including cooperative presser surfaces between which said strips pass, and means adapted to heat one of said presser surfaces.

75 4. In an apparatus of the character described, in combination, mechanism adapted to feed a backing strip, a facing strip and a reinforcing strip into superposed relation, including presser rolls between which pass the parts of the strips to be attached 80 together, and movable pins alongside said presser rolls adapted to advance the parts of said strips at the side of said presser rolls.

85 5. In an apparatus of the character described, in combination, mechanism adapted to feed a backing strip, a facing strip and a reinforcing strip into superposed relation, means adapted to attach said strips together along a predetermined line, and 90 means co-operative with the aforesaid parts whereby said facing strip is attached in shirred condition.

95 6. In an apparatus of the character described, in combination, mechanism adapted to feed a backing strip, a facing strip and a reinforcing strip into superposed relation, means adapted to attach said strips together along a predetermined line, and a facing strip shirring device operative in 100 front of said attaching means.

105 7. In an apparatus of the character described, in combination, mechanism adapted to feed a backing strip, a facing strip and a reinforcing strip into superposed relation, including presser rolls between which portions of said strips pass, pin feeding devices for advancing portions of said backing and facing strips at the side of said pressed portions, and a shirring device operative to shir said facing strip in front of 110 said presser rolls.

115 8. In an apparatus of the character described, in combination, mechanism adapted to feed a backing strip, a facing strip and a reinforcing strip into superposed relation, including presser rolls between which portions of said strips pass, pin feeding devices for advancing portions of said backing and facing strips at the side of said pressed portions, a shirring device operative to shir said facing strip in front of 120 said presser rolls, and a liquid coating device disposed to operate on said reinforcing strip prior to its attachment.

125 9. In an apparatus of the character described, in combination, mechanism adapted to feed a backing strip, a facing strip and a reinforcing strip into superposed relation, including presser rolls between which 130

- 6
- portions of said strips pass, pin feeding devices for advancing portions of said backing and facing strips at the side of said pressed portions, a stirring device operative to stir said facing strip in front of said presser rolls, a liquid coating device disposed to operate on said reinforcing strip prior to its attachment, and means adapted to heat one of said presser rolls.
- 10 10. In an apparatus of the character described, in combination, mechanism adapted to feed a backing strip, a facing strip and a reinforcing strip into superposed relation, including a device adapted to attach said strips together along a predetermined line, a finishing strip supply, a folder for said finishing strip, and means adapted to attach said finishing strip in folded condition over the attached portions of said other strips.
- 15 11. In an apparatus of the character described, in combination, mechanism adapted to feed a backing strip, a facing strip and a reinforcing strip into superposed relation, including a device adapted to attach said strips together along a predetermined line, and means adapted to slit the attached strips within their area of attachment.
- 20 12. In an apparatus of the character described, in combination, mechanism adapted to feed a backing strip, a facing strip and a reinforcing strip into superposed relation, including a device adapted to attach said strips together along a predetermined line, means adapted to slit the attached strips within their area of attachment, a plurality of supplies of finishing strip, and means adapted to attach said finishing strips to the edges respectively produced by said slitting operation.
- 25 13. In an apparatus of the character described, in combination, mechanism adapted to feed a backing strip, a facing strip and a reinforcing strip into superposed attached relation along a predetermined line, means adapted to slit the attached strips within their area of attachment, a plurality of supplies of finishing strip, means adapted to fold said finishing strips, and means adapted to attach said finishing strips to the edges respectively produced by said slitting operation.
- 30 14. In an apparatus of the character described, in combination, a pair of rolls having co-operative presser portions, and pin feeding devices at the side of said presser portions.
- 35 15. In an apparatus of the character described, in combination, a pair of rolls having co-operative presser portions, pin feeding devices at one side of said presser portions, and means adapted to operate one of said pin feeding devices at a greater rate of speed than the other.
- 40 16. In an apparatus of the character de-
- scribed, in combination, a pair of rolls having co-operative presser portions, pin feeding devices at one side of said presser portions, means adapted to operate one of said pin feeding devices at a greater rate of speed than the other, and a stirring blade operative in front of said rolls.
- 45 17. In an apparatus of the character described, in combination, a backing strip feed roll and belt, pins carried by said belt to positively advance said strip, a facing strip feed roll shaft opposite said backing strip feed belt, and pins carried by said shaft to advance the backing strip, said roll and shaft having co-operative presser portions at the side of said pins.
- 50 18. In an apparatus of the character described, in combination, a backing strip feed roll and belt, pins carried by said belt to positively advance said strip, a facing strip feed roll shaft opposite said backing strip feed belt, pins carried by said shaft to advance the backing strip, said roll and shaft having co-operative presser portions at the side of said pins, and means adapted to drive said shaft at a greater rate of speed than said backing strip roll.
- 55 19. In an apparatus of the character described, in combination, a backing strip feed roll and belt, pins carried by said belt to positively advance said strip, a facing strip feed roll shaft opposite said backing strip feed belt, pins carried by said shaft to advance the backing strip, said roll and shaft having co-operative presser portions at the side of said pins, means adapted to drive said shaft at a greater rate of speed than said backing strip roll, and a stirring device operative on the facing strip in front of said rolls.
- 60 20. In an apparatus of the character described, in combination, a backing strip feed roll and belt, pins carried by said belt to positively advance said strip, a facing strip feed roll shaft opposite said backing strip feed belt, pins carried by said shaft to advance the backing strip, said roll and shaft having co-operative presser portions at the side of said pins, means adapted to drive said shaft at a greater rate of speed than said backing strip roll, a stirring device operative on the facing strip in front of said rolls, and a liquid coating device disposed to coat a reinforcing strip fed between the backing and the facing strips.
- 65 21. In an apparatus of the character described, in combination, a backing strip feed roll and belt, pins carried by said belt to positively advance said strip, a facing strip feed roll shaft opposite said backing strip feed belt, pins carried by said shaft to advance the backing strip, said rolls having co-operative presser portions at the side of said pins, and means whereby the pressure between said rolls may be adjusted.

22. In an apparatus of the character described, in combination, a pair of co-operative pressing devices between which strips pass for attachment together at the pressed areas, means adapted to advance a transversely folded portion of one of said strips for attachment to the other strips by said pressing devices, and devices, operative on one or more of said strips at the side of the areas to be so attached, to advance such side portions so that the widths of the strips are advanced substantially uniformly. 70
23. In an apparatus of the character described, in combination, a pair of co-operative pressing devices between which strips pass for attachment together at the pressed areas, means adapted to advance a transversely folded portion of one of said strips for attachment to the other strips by said pressing devices, and devices, operative on one or more of said strips at the side of the areas to be so attached, to advance such side portions so that the widths of the strips are advanced substantially uniformly, said pressing devices including a pair of co-operative presser rolls. 80
24. In an apparatus of the character described, in combination, a pair of co-operative pressing devices between which strips pass for attachment together at the pressed areas, means adapted to advance a transversely folded portion of one of said strips for attachment to the other strips by said pressing devices, and devices, operative on one or more of said strips at the side of the areas to be so attached, to advance such side portions so that the widths of the strips are advanced substantially uniformly, said advancing means including a strip folding blade. 90
25. In an apparatus of the character described, in combination, a pair of co-operative pressing devices between which strips pass for attachment together at the pressed areas, means adapted to advance a transversely folded portion of one of said strips for attachment to the other strips by said pressing devices, and devices, operative on one or more of said strips at the side of the areas to be so attached, to advance such side portions so that the widths of the strips are advanced substantially uniformly, said side advancing devices including tractive fingers adapted to co-operate with the strip to be folded at one side of said pressing devices. 100
26. In an apparatus of the character described, in combination, a pair of co-operative pressing devices between which strips pass for attachment together at the pressed areas, means adapted to advance a transversely folded portion of one of said strips for attachment to the other strips by said pressing devices, and devices, operative on one or more of said strips at the side of the areas to be so attached, to advance such side portions so that the widths of the strips are advanced substantially uniformly. 110
27. In an apparatus of the character described, in combination, a pair of co-operative pressing devices between which strips pass for attachment together at the pressed areas, means adapted to advance a transversely folded portion of one of said strips for attachment to the other strips by said pressing devices, and devices, operative on one or more of said strips at the side of the areas to be so attached, to advance such side portions so that the widths of the strips are advanced substantially uniformly, said pressing devices including a pair of co-operative presser rolls and said side advancing devices including tractive fingers adapted to co-operate with the strip to be folded at one side of said pressing devices. 120
28. In an apparatus of the character described, in combination, a pair of co-operative pressing devices between which strips pass for attachment together at the pressed areas, means adapted to advance a transversely folded portion of one of said strips for attachment to the other strips by said pressing devices, and devices, operative on one or more of said strips at the side of the areas to be so attached, to advance such side portions so that the widths of the strips are advanced substantially uniformly, said fold advancing means including a strip folding blade and said side advancing devices including tractive fingers adapted to co-operate with the strip to be folded at one side of said pressing devices. 130
29. In an apparatus of the character described, in combination, a pair of co-operative pressing devices between which strips pass for attachment together at the pressed areas, means adapted to advance a transversely folded portion of one of said strips for attachment to the other strips by said pressing devices, and devices, operative on one or more of said strips at the side of the areas to be so attached, to advance such side portions so that the widths of the strips are advanced substantially uniformly, said pressing devices including a pair of co-operative presser rolls, said fold advancing means including a strip folding blade and said side advancing devices including tractive fingers adapted to co-operate with the strip to be folded at one side of said pressing devices. 140
30. In an apparatus of the character described, in combination, a pair of co-operative pressing devices between which strips pass for attachment together at the pressed areas, means adapted to advance a transversely folded portion of one of said strips

- for attachment to the other strips by said pressing devices, and devices, operative on one or more of said strips at the side of the areas to be so attached, to advance such side portions so that the widths of the strips are advanced substantially uniformly, said side advancing devices including sets of tractive fingers on opposite sides of the plane of attachment, adapted to co-operate with the outer strips at one side of said pressing devices.
31. In an apparatus of the character described, in combination, a pair of co-operative pressing devices between which strips 15 pass for attachment together at the pressed areas, means adapted to advance a transversely folded portion of one of said strips for attachment to the other strips by said pressing devices, and devices, operative on one or more of said strips at the side of the areas to be so attached, to advance such side portions so that the widths of the strips are advanced substantially uniformly, said side advancing devices including 20 sets of tractive fingers on opposite sides of the plane of attachment, adapted to co-operate with the outer strips at one side of said pressing devices, one of said sets including strip penetrative fingers.
32. In an apparatus of the character described, in combination, a pair of co-operative pressing devices between which strips pass for attachment together at the pressed areas, means adapted to advance a transversely folded portion of one of said strips for attachment to the other strips by said pressing devices, and devices, operative on one or more of said strips at the side of the areas to be so attached, to advance such side portions so that the widths of the strips are advanced substantially uniformly, said side advancing devices including sets of tractive fingers on opposite sides of the plane of attachment, adapted to co-operate with the outer strips at one side of said pressing devices, one of said sets including friction fingers.
33. In an apparatus of the character described, in combination, a pair of co-operative pressing devices between which strips pass for attachment together at the pressed areas, means adapted to advance a transversely folded portion of one of said strips for attachment to the other strips by said pressing devices, and devices, operative on one or more of said strips at the side of the areas to be so attached, to advance such side portions so that the widths of the strips are advanced substantially uniformly, said side advancing devices including sets of tractive fingers on opposite sides of the plane of attachment, adapted to co-operate with the outer strips at one side of said pressing devices, one of said sets including strip penetrative fingers.
34. In an apparatus of the character described, in combination, mechanism adapted to feed a backing strip, a facing strip 70 and a reinforcing strip into superposed relation, said mechanism including a belt having means to engage and positively feed the backing strip and a roll having friction pins to engage and feed the facing strip, and means adapted to attach said strips together along a predetermined line.
35. In an apparatus of the character described, in combination, mechanism adapted to feed a backing strip and a facing strip 80 into superposed relation, said mechanism including a belt having pins to engage and feed the backing strip, and a roll having friction pins to engage and feed the facing strip, and means adapted to attach such 85 strips together along a predetermined line.
36. In an apparatus of the character described, in combination, mechanism adapted to feed a backing strip and a facing strip 90 into superposed relation, means adapted to attach said strips along a predetermined line, and means cooperative with the aforesaid parts whereby said facing strip is attached in shirred relation.
37. In an apparatus of the character described, in combination, mechanism adapted to feed a backing strip and a facing strip into superposed relation, means adapted to attach said strips together along a predetermined line, and a facing strip shirring device 95 operative in front of said attaching means.
38. In an apparatus of the character described, in combination, mechanism adapted to feed a backing strip and a facing strip into superposed relation, including presser 100 rolls between which portions of said strips pass, in feeding devices for advancing portions of said backing and facing strips at the side of said pressed portions, and a shirring device operative to shirr and facing 110 strip in front of said presser rolls.
39. In an apparatus of the character described, in combination, mechanism adapted to feed a backing strip and a facing strip into superposed relation, including a device 115 adapted to attach said strips together along a predetermined line, a finishing strip supply, a folder for said finishing strip, and means adapted to attach said finishing strip in folded condition over the attached portions of said other strips.
40. In an apparatus of the character described, in combination, mechanism adapted to feed a backing strip and a facing strip into superposed relation, including a device 120 adapted to attach said strips together along a predetermined line, means adapted to slit the attached strips within their area of attachment, a plurality of supplies of finishing strip, and means adapted to attach said 125 strips.

finishing strips to the edges respectively produced by said slitting operations.

41. In an apparatus of the character described, in combination, mechanism adapted to feed a backing strip and a facing strip into superposed relation, including a device adapted to attach said strips together along a predetermined line, means adapted to slit the attached strips within their area of attachment, a plurality of supplies of finishing strip, means adapted to fold said finishing strips, and means adapted to attach said finishing strips to the edges respectively produced by said slitting operation.
- 15 42. In an apparatus of the character de-

scribed, in combination, mechanism adapted to feed a backing strip and a facing strip into superposed relation, said mechanism including a belt having means to engage and positively feed the backing strip, and a roll 20 having friction pins to engage and feed the facing strip, and means adapted to attach said strips together along a predetermined line.

In testimony whereof I affix my signature, 25 in the presence of two witnesses.

HARRY TAYLOR LOOMIS.

Witnesses:

CATHARINE LEDDEN,
EDWIN HAMPTON.

Certificate of Correction.

It is hereby certified that in Letters Patent No. 1,468,483, granted September 18, 1923, upon the application of Harry Taylor Loomis, of Brooklyn, New York, for an improvement in "Fabric-Making Machines," errors appear in the printed specification requiring correction as follows: Page 7, line 38, claim 24, for the misspelled word "uinformily" read *uniformly*; page 8, line 107, claim 38, for the word "in" read *in*, and line 110, for the word "and" read *said*; and that the said Letters Patent should be read with these corrections therein that the same may conform to the record of the case in the Patent Office.

Signed and sealed this 23d day of October, A. D., 1923.

[SEAL.]

WM. A. KINNAN,
Acting Commissioner of Patents.
